UNITED STATES PATENT OFFICE.

ANDREW H. WEIR, OF LOS ANGELES, ASSIGNOR OF ONE-HALF TO JAMES O'BANNON, OF SAN GABRIEL, CALIFORNIA.

CAR-COUPING.

SPECIFICATION forming part of Letters Patent No. 461,527, dated October 20, 1891.

Application filed November 14, 1890, Serial No. 371,398. (No model.)

To all whom it may concern:

Be it known that I, ANDREW H. WEIR, a citizen of the United States, residing at Los Angeles, in the county of Los Angeles and 5 State of California, have invented a new and useful Improvement in Car-Couplings, of which the following is a specification.

The object of my invention is to provide means whereby the ordinary link-and-pin 10 coupling can be employed in coupling cars without any danger to life or limb.

My invention consists, essentially, of a gravity-pin support and dropper comprising a bar suspended in the path of the link by suitable 15 swings and arranged to normally swing forward and project into the mouth of the draw-bar across the path of the pin to sustain the pin in position to allow the insertion of the link and to swing out of the path of the pin 20 when engaged by the link forced into the draw-head in the act of coupling.

I am aware that there have heretofore been employed link-operated pin-dropping devices, and do not broadly claim a link-operated pin- 25 dropping device as my invention; but my invention consists of various features of construction and combinations of parts, hereinafter described and claimed, and illustrated in the accompanying drawings, in which—

30 Figure 1 is a vertical longitudinal section of two draw-heads provided with my invention and in the act of coupling. In this view one of the draw-heads is shown as being higher than the other to illustrate the operation of 35 the improved draw-head when the draw-heads are of different heights. Fig. 2 is a top view of the draw-head with the front part of its top broken away to expose the link guideway formed by the curved flaring face of the lower lip of the draw-head. In 40 this figure the pin-support and the dropper-bar A is shown in its forward or normal position. Dotted lines show it in its retracted position. Fig. 3 is a front elevation looking 45 into the mouth of the draw-head. Fig. 4 is a plan elevation showing my improved pin-pulling attachment above a draw-bar, with the pin drawn. Fig. 5 is a vertical mid-section of the attachment when lowered to allow the pin 50 to be inserted.

My improved pin support and dropper com-

prises a swinging or oscillating gravity-bar A, provided with the clevis-holes E F and provided with the top forward extension extended beyond the front clevis-hole E and 55 forming the pin-supporting nose b. This gravity-bar is suspended substantially horizontal in the draw-bar B and parallel with the axis thereof. It is supported by the clevises or swings C D, which are respectively 60 passed through the holes E F in the bar A and pivoted to the draw-bar by bolts G H, passed through the eyes I in the ends of the clevises, and secured in the draw-bar, preferably by stoving their ends, as indicated in 65 Fig. 2.

In order to prevent the pin support or dropper from being oscillated by the motion of the car and thus acquiring sufficient momentum to swing back to release the pin, I provide 70 the front stop J to engage the throat j of the draw-head to hold the bar A far enough back to throw the rear clevis D out of the perpendicular, thus raising the rear end of the bar A, so that the bar is held pressed forward by 75 its gravity, and the initial movement of any oscillation must raise the rear end of the bar. To increase this effect, the rear bolt H is higher than the front bolt G and the rear clevis D is longer than the front clevis C, thus 80 giving the required elevation to the rear end of the bar without thereby limiting its backward swing.

In order to prevent any upward movement of the front end of the bar which might throw 85 the pin out of the draw-head, the hole E, through which the front clevis C passes, is in the form of a slot longitudinal of the bar and having its top slightly curved up at the front end, so that at the initial rearward movement of the bar the clevis C slips in its slot, or, more properly, the slotted bar moves back without moving the front clevis until the end of the slot engages the clevis, thus throwing it back and raising the bar at its front end as 90 well as the rear, so that the rear end of the bar is raised at its initial backward movement more rapidly than it would be were the rear clevis to normally hang perpendicular. This rapid elevation of the rear end causes 95 the front end to tip down more suddenly, and this downward movement is increased by the 100

slight upward curve *h* of the top of the slot. The rear clevis is longer than the front clevis and its pivot is higher than the pivot of the front clevis, in order that when the bar is 5 swung back the swing of the rear clevis will be sufficient to allow the bar to move back the length of the slot *E* and the full swing of the front clevis also. The rear clevis, its pivot, the bar, and its stop are arranged with 10 such relation to each other that when the bar is in its normal position the lower end is held back the sixteenth of a circle, more or less. By this contrivance the rear end of the bar is raised and the front end is lowered simultaneously 15 at the initial backward movement of the bar, and at its final rearward movement the bar is lifted bodily if it is thrown back far enough to swing the front clevis, except, however, the extreme front end, which then moves back substantially on a horizontal line. This contrivance enables me to provide still further means for preventing the oscillating of the dropper by making a slight pin-retaining elevation *a* on the top of the pin-supporting nose or nib *b*. This elevation engages the pin *L*, and thus assists to prevent the bar from moving backward unless impelled with considerable force, so as to drive it quickly, as in the act of coupling. The sudden downward 20 movement of the front end just described allows the elevation *a* to pass the pin without raising it.

c represents the link-shoulder underneath the pin nose or nib *b*, and against which the 30 link *e* strikes in the act of coupling. In order to guide the link into its proper seat in the draw-head or bar *B*, I construct the mouth of the draw-head of a peculiar form. The upper face of its lower lip is vertically broad, 35 and is inclined upward and backward, and is dished or curved inward from the side walls *d* and back toward the pin-hole *C*—that is to say, the mouth of the draw-head is provided with a broad inclined downward and outwardly flaring lip, the upper edge of which at 40 its junction with the floor *N* of the link-receptacle forms two lateral forwardly-projecting link-supporting shoulders *n*. In addition to this the inclined lip *M* is vertically broad, 45 so that it will receive the link in case the link should droop or in case the opposing draw-head should be higher than the head in which the link is inserted, as shown in Fig. 1. The curved and inclined flaring face *m* of the under lip receives the rounded end of the link 50 and guides it into the exact central position required for it to receive the pin. This feature avoids all necessity of the operator guiding the link into place with his hand or with 55 a stick, as is customary with link-couplings. The top edge of the face *m* of the flaring lip is crescent-shaped, as shown in Fig. 2, and when the link is in position in the draw-head 60 its parallel side arms will rest upon the shoulders *n*, formed by the horns of the crescent, thus bringing the point of support nearer the middle of the link than has heretofore been

the case in flaring-mouth draw-heads. The nose or nib *b* is arranged to leave between it and the floor *N* of the link-receptacle a space 70 slightly less than the thickness of the link, so that the weight of the front end of the bar, in conjunction with the shoulders *n*, will tend to prevent the free end of the link from drooping. If the link should droop, thus raising the front end of the gravity-bar, the weight of such bar will tend to cause the link to more easily slide up the inclined lip *m* of the draw-head when coupling. In order to prevent the bar *A* from binding, the front clevis 75 slot *E* is of greater width vertically than the diameter of the clevis passing therethrough, so that the front end of the bar may be lifted slightly without binding against the clevis. The roof of the mouth of the draw-head is 80 sloped and dished or channeled from the extreme front downward and backward to the link-seat behind the pin-hole, so as to guide the end of the link properly when the end of the link chances to be elevated and engages 85 the roof of the mouth instead of the lower lip.

The pin-pulling attachment consists of the combination of the journaled rod *P*, provided with the cranks or handles *Q Q'*, the pin-pulling arm *R*, and the side stops *S S'*, the central arc stop *T*, and the chain *U*, secured to the pin. The rod *P* is journaled in bearings *V*, secured to the end of the car *X* and provided with the side shoulders *v v'* to receive the stops *S S'* when it is desired to hold the 100 pin in its elevated position. The stops *S* and *S'* are arranged to allow the bar to play longitudinally and are arranged to play freely past the shoulders *v v'* when the pin-pulling arm is midway of the arc stop *T*. When it is 105 desired to draw the pin without entering between the cars, the crank *Q* or *Q'* is raised, thus raising the end of the arm *R* and withdrawing the pin until the arc comes into contact with the top arm of arc stop *T*. The pin, 110 arm, chain, and arc stop are so proportioned and arranged with relation to each other that the arm strikes the stop when the pin has been raised far enough to allow the pin-dropper to swing forward under it. The arc 115 stop may be of wood, either with or without an iron facing *f*, and the movement of the arm may be gaged by adding to or taking from the upper or lower arms *t t'*, as may be desired, to allow the proper sweep of the arm. 120

In operation the pin is drawn by operating the handle, as above set forth, and then, if it is desired to hold the pin in its elevated position, the rod is drawn or pushed bodily endwise, thus bringing the stop *S* or *S'*, as the case may be, into position to engage the shoulder *v* or *v'*, thus to hold the arm *R* in its elevated position. To release it the rod is again moved endwise, so that the stops will not engage the shoulders.

The puller-rod *P* is formed of a single piece bent to form the arm and the handles, and the stops may be pins inserted through the rod.

While the pin-dropping device and the pin-

puller may be used separately, I prefer to use them combined to form a complete coupling device, as shown in Fig. 4.

Now, having described my invention, what I claim as new, and desire to secure by Letters Patent, is—

1. In a car-coupling, the pin support and dropper comprising a bar suspended in the path of the link by suitable swings, substantially as set forth.

2. In a car-coupling, the combination of the draw-bar, the gravity-bar provided with the clevis-holes and provided with the forward extension extending beyond the front clevis-hole to form the pin-supporting nose, and the clevises passed through the clevis-holes and pivoted at their upper ends to the draw-bar.

3. In a car-coupling, the combination of the draw-bar, the gravity-bar provided with the rear clevis-hole and the front oblong clevis-hole and provided with the top forward extension extending beyond the front clevis-hole to form the pin-supporting nose, and the clevises passed through the clevis-holes and pivoted at their upper ends to the draw-bar.

4. In a car-coupling, the combination of the draw-bar, the gravity-bar provided with the rear clevis-hole and the front oblong clevis-hole, the front stop, and the forward extension extending beyond the front clevis-hole to form the pin-supporting nose, the front and rear clevises passed through the clevis-hole and pivoted to the draw-bar at their upper ends and so arranged with relation to the

stop that when in the normal position the lower end of the rear clevis is held back, substantially as and for the purpose set forth.

5. In a car-coupling, the combination of the pin, the draw-bar, the gravity-bar provided with the rear clevis-hole and the oblong front clevis-hole and provided with the top forward extension extending beyond the front clevis-hole to form the pin-supporting nose and provided with the slight pin-retaining elevation, and the front and rear clevises pivoted to the draw-bar.

6. In a car-coupling substantially such as set forth, the gravity-bar having the front end of the top of its oblong front clevis-hole slightly curved upward, as and for the purpose set forth.

7. In a car-coupling, the combination of the draw-bar provided with the link-supporting shoulders, the link, and the gravity-pin supporter and dropper provided with the forwardly-projecting nose to rest upon the point of the link.

8. In a car-coupling, the pin-pulling device comprising the combination of the bearings secured to the end of the car and provided with the shoulders, the journaled rod provided with the handles, the pin-pulling arm, the side stops, the central arc stop, and the chain and pin.
